(57) **CLAIM**

The ornamental design for a benchtop saw with blade guard and slideable fence, as shown and described.

DESCRIPTION

FIG. 1 is a front top right perspective of a benchtop saw with blade guard and slideable fence of the present invention with the slideable fence perpendicular to the blade guard; FIG. 2 is a front elevation of the benchtop saw with blade guard and slideable fence of FIG. 1;

FIG. 3 is a rear elevation of the benchtop saw with blade guard and slideable fence of FIG. 1;

FIG. 4 is a right side elevation of the benchtop saw with blade guard and slideable fence of FIG. 1;

FIG. 5 is a left side elevation of the benchtop saw with blade guard and slideable fence of FIG. 1;

FIG. 6 is a top plan view of the benchtop saw with blade guard and slideable fence of FIG. 1

FIG. 7 is a bottom plan view of the benchtop saw with blade guard and slideable fence of FIG. 1.

FIG. 8 is a front top right perspective of the benchtop saw with blade guard and slideable fence of FIG. 1 with the slideable fence in an angular orientation relative to the blade guard; and,

FIG. 9 is a front top right perspective of the benchtop saw with blade guard and slideable fence of FIG. 1 with the slideable fence parallel to the blade guard.

The dash-dash-dash type broken lines shown in the drawings are included for the purpose of illustrating environmental structure and form no part of the claimed design. The broken lines show portions of a benchtop saw with blade guard and slideable fence which form no part of the claimed design.
